UNITED STATES PATENT OFFICE.

RALPH BOWN, OF MAPLEWOOD, NEW JERSEY, AND HAROLD S. HAMILTON, OF NEW YORK, N. Y., ASSIGNEES TO AMERICAN TELEPHONE AND TELEGRAPH COMPANY, A CORPORATION OF NEW YORK.

RADIO TRANSMISSION SYSTEM.

Application filed December 18, 1924. Serial No. 756,803.

This invention relates to radio transmission systems and more particularly to arrangements for improving the operation of radio circuits used for long distance transmission.

In order to operate a radio telephone transmission system on a two-way basis where the intercommunicating stations are widely separated, as, for example, in trans-Atlantic communication, many problems arise which are not met with in the usual radio practice. For example, it is necessary that some part of the system, frequently including the high frequency part of the system, be operated on a four-wire basis and connected to terminal two-wire connections. A circuit of this type has a tendency to be unstable due to poor hybrid coil balances or to variations in the transmission equivalent of the high frequency part of the circuit.

This difficulty may be overcome, as herein disclosed, by associating echo suppressors with the four-wire part of the system, these elements operating to disable the circuit for transmission in one direction in response to the transmission of currents in the opposite direction. Preferably, also, the echo suppressor units may be arranged to normally disable the circuit to the radio transmitter to prevent local singing.

In accordance with the present invention it is further proposed to provide means to enable the circuit to be operated not only when the hybrid coil balances or the radio circuit transmission equivalents are at unsuitable values for ordinary operation, but also when the radio loss from the local transmitter into its associated local receiver is insufficient to prevent singing or poor quality. The last mentioned condition becomes particularly pronounced when the system is designed to transmit in both directions at the same radio frequency, and this is almost necessary in a trans-oceanic radio telephone system in order to conserve the frequency range. Under such conditions the tendency of the local circuit to sing, due to the transfer of energy around the circuit from the local radio transmitter to the local radio receiver, may be overcome by providing a pair of echo suppressor units at each of the two widely separated communicating points. Each local four-wire circuit will then have its transmitter normally disabled to prevent

singing and the echo suppressor units will respond to voice currents to disable either one of the paths of the four-wire part of the local circuit, while enabling the other path to carry transmission, depending on the direction in which signaling is taking place.

The invention may now be more fully understood from the following description when read in connection with the accompanying drawing, Figures 1 and 2 of which, when placed end to end, illustrate the circuits whereby two widely separated points may be put into two-way communication by radio telephony.

Referring to the drawing, L designates an ordinary telephone line entering a telephone exchange at some point. The line L terminates in the usual hybrid coil 10 and balancing network N, the hybrid coil 10 serving to connect the line to a transmission path LE for transmission from west to east and a transmission path LW for transmission from east to west. The transmission path LE includes suitable amplifiers or repeaters such as RE₁, RE₂ and extends to a suitable location for a radio transmitter comprising a radiating antenna AT and radio transmitting apparatus TT, schematically indicated in the drawing. Similarly, the transmission path LW includes suitable one-way amplifiers or repeaters RW₄ and RW₃ and extends to a radio receiving apparatus, schematically indicated at RR, and located at some suitable point which is not too close to the transmitting station.

In order to enable the system to transmit only in one direction at a time and in order to prevent singing or noisy conditions of the four-wire part of the circuit, an echo suppressor unit may be located at any point, as, for example, an intermediate repeater point. In the case illustrated the echo suppressor combination is located at the repeater station including the repeaters RE₂ and RW₃. The echo suppressor comprises two separate units or elements, one for controlling transmission in one direction and the other for controlling transmission in the other direction. For example, the element associated with the transmission path LE comprises an amplifier-detector arrangement VE of a type well known in the art. Similarly, the unit associated with the path LW comprises a similar amplifier-detector arrangement VW. The

latter amplifier-detector unit has in circuit therewith a relay which responds to rectified voice currents transmitted over the path LW to actuate a contact 1, thereby short-circuiting and disabling the path LE. The amplifier-detector unit VE, on the other hand, has in circuit therewith a relay controlling contacts 2 and 3. Contact 3 normally short-circuits the path LE, so that when the circuit is idle noise currents originating in the circuit LE will not be transmitted to the radio receiver and back through the path LW and the hybrid coil 10 to the path LE to set up singing or noisy conditions of the circuit. The relay operates in response to rectified voice currents transmitted over the circuit LE to close the contact 2 to short-circuit the path LW and therefore disable the circuit for transmission from east to west. At the same time the contact 3 is opened to render the path LE operative for transmission from west to east. A delay network X is inserted between the point at which the amplifier-detector unit VE is connected and the short-circuit connections of the contact 3 to enable the contact 3 to be opened before the voice currents arrive at the point where the short-circuit is applied.

In order to reduce the transmission from the transmitting antenna AT to the local radio receiver RR, particularly where transmission and reception both take place at the same wave length, a wave antenna AR may be employed, which has a directive effect. The wave antenna, as illustrated, comprises a pair of conductors 11 and 12 extended horizontally at a suitable point above the ground to a distance of one or more wave lengths. These conductors act as an antenna upon which the wave coming from the right, for example, builds up by successive increments so that it reaches its maximum amplitude at the antenna terminal at the left. The waves picked up by the two conductors 11 and 12 of the antenna are transmitted through a ground connection 13, including the primary winding of a transformer 14. In order that the waves thus received may affect the receiving instrument connected to the opposite end of the antenna conductors a secondary winding 15 is inductively associated with the winding 14 to connect the two conductors 11 and 12 in series. As a result the waves built up on the antenna conductors 11 and 12 in parallel are transmitted back over the conductors 11 and 12, connected in series with each other so that they form a line circuit. The waves at the receiving end are then passed through a transformer 16 and applied to the radio receiver RR through a suitable amplifier 17.

Assuming that transmission and reception take place on different wave lengths and that the energy transmitted from the transmitting antenna AT to the receiving apparatus RR

is so small, by reason of the selectivity of the circuit and the directive reception of the antenna, that singing will not take place locally from the antenna AT to the radio receiver RR and thence around through the hybrid coil 10, the system will operate for two-way communication with a similar circuit at a distant point without requiring the provision of a second pair of echo suppressor units for the circuit at the distant point. The contact 3, which is normally closed to short-circuit the conductor LE, prevents singing about the complete four-wire path including the radio circuits at both widely separated points and also prevents the transmission of noise currents over the circulatory path including the two radio frequency channels; that is to say, noise currents or singing currents set up in the radio transmitter TT and radiated at one wave length through the ether to the distant receiving apparatus, then transmitted at low frequencies over the west to east transmission path to the hybrid coil at the distant point, thence through said hybrid coil over the east to west path to the transmitter at the distant point, from whence the currents are radiated at another radio frequency, received by the wave antenna AR, translated to voice frequencies by the receiver RR and transmitted over the path LW and through the hybrid coil 10 and thence over the path LE, will be prevented from being transmitted to the radio transmitter TT and again radiated by reason of the short circuit at the contact 3. Such circulatory transmission, in short, cannot take place in the normal condition of the circuit and it is not necessary to provide a second pair of echo suppressor units at the distant station to prevent such circulatory transmission.

If a subscriber at one point speaks to a subscriber at the distant point the voice currents incoming from the line L will pass through the hybrid coil 10 to the path LE and after being amplified by the repeaters RE₁ and RE₂ will be impressed on the delay network X. Part of the energy is diverted, however, into the amplifier-detector unit VE and operates the relay to close the contact 2 and open the contact 3. The closure of contact 2 disables the path LW so that transmission from the distant station cannot be received. Contact 3 in the meantime is opened before the voice wave passes through the delay network X so that the path from west to east is now operative through to the distant receiving point. The wave then passes through the filter TF to the radio transmitter TT and is translated to a radio frequency for transmission from the antenna AT. The subscriber at the distant end cannot break in to talk in the reverse direction until the subscriber who is now talking interrupts his conversation.

When the subscriber at the distant point talks the voice currents are transmitted over a similar transmission circuit from east to west and are radiated from the transmitting station at the distant point at a different wave length from that employed for transmission from west to east. Upon being received by the wave antenna AR the waves are impressed through the amplifier 17 upon the radio receiver RR. The voice waves are detected by the receiver and transmitted through the filter RF to the east to west path LW and after being amplified by the amplifier RW₃ are transmitted on to the second amplifier RW₄. A part of the energy is diverted into the amplifier-detector unit VW to close the contact 1. The contact 2 is, of course, normally open and contact 3 is closed. The operation of the contact 1 short-circuits the path LE and also prevents the transmission of energy from the path LE to the amplifier-detector unit VE. This operation takes place before the voice wave passing from the output of the repeater RW₃ has had time to pass through the hybrid coil 10 and back over the path LE to the delay network. When the voice currents have passed to this point they will be blocked by the short circuit established at the contact 1. The transmission path from west to east is therefore completely blocked but transmission may take place freely from east to west. The received voice currents passed through the repeater RW₄ are, of course, transmitted over the line L to the subscriber.

Where transmission in both directions takes place at the same wave length, as must frequently be the case in order to conserve space in the frequency spectrum, the provision of a pair of echo suppressor units in connection with one of the four-wire circuits at one of the intercommunicating points is not sufficient to enable the system to operate. The amount of energy radiated from the local transmitting antenna to the local receiving antenna (even where the receiving antenna is balanced by directivity or other means with respect to the transmitting antenna) is very great and singing may take place from the transmitting antenna to the local receiving antenna at the distant point and over the four-wire local circuit at the distant point because no echo suppression apparatus is provided there. While this singing is prevented in connection with the circuit of Fig. 1, the singing at the distant intercommunicating point will prevent the use of the circuit for two-way communication. In order to provide for this difficulty the circuit at the distant point, which is illustrated in Fig. 2, must also be provided with echo suppression units. The apparatus of the circuit of Fig. 2 is now in all respects similar to that shown in Fig. 1, the

corresponding parts being designated by the same reference characters primed. It will be noted that in Fig. 2 the contact 3', controlled by the echo suppressor unit VW', is normally closed, thereby disabling the transmission path LW' and preventing singing due to the transmission of energy from the radio transmitter TT' to the radio receiver RR' and thence over the path LE' through the hybrid coil 10' and back over the path LW'. Similarly, the normally closed circuit 3 of Fig. 1 prevents singing over the local four-wire circuit at the other end. The contacts 3 and 3' therefore perform two functions. They prevent singing over the local four-wire circuits at the two distant ends of the system and they furthermore prevent circulation of energy from the hybrid coil 10 over the complete channel from west to east to the hybrid coil 10' and thence back over the complete channel from east to west to the hybrid coil 10.

If a subscriber at the west station of the system desires to talk to a subscriber at the east station, the voice currents passing over the circuit LE will operate the amplifier-detector unit VE as before to close the short-circuit at 2 and open the short-circuit at 3. The path LE is now operative and the path LW is inoperative. Local singing still cannot take place for one of the paths (the path LW) is inoperative. The voice currents operate the radio transmitter TT to cause transmission at the chosen wave length from the antenna AT to the distant receiving wave antenna AR'. This receiving antenna is similar to that described in connection with Fig. 1 and operates in a similar manner to pick up the waves over the two sides of the circuit in parallel and transfer them back over the conductor wires in series as a transmission line, the waves then being passed through an amplifier 17' to the radio receiver RR'. Upon being detected, the voice currents are transmitted over the path LE' and through the repeater RE'. The amplified voice currents now operate the amplifier-detector unit VE' to close the short-circuit 1'. The path LW' is already disabled at a short circuit controlled by the contact 3' but the closing of the contact 1' prevents any possibility of the voice-operated unit VW' responding to echo currents or to transmission from the subscriber at the east station during the time the voice waves are traveling from the west station. The voice waves pass on through the repeater RE', and thence into the line L'. It will be obvious that as long as the voice waves are being transmitted the circuit is completely operative through in the direction from west to east and the circuit from east to west is inoperative. This inoperativeness is established at both ends of the system and therefore local singing cannot

take place at the two ends. The voice currents incoming to the line L' cannot therefore pass through the path LW' to be re-radiated by the transmitter TT' .

5 When the transmission of voice currents from west to east ceases the subscriber at the east station can talk in the opposite direction, in which case the echo suppressor units VW' and VW will be operated successively to disable the circuit from west to east and open the circuit through from east to west in a manner similar to that already described. Singing around the entire circuit including the east and west terminals 10 is impossible when echo suppressors are provided at both ends for the same reasons that apply when the echo suppressor arrangements are placed at one end only of the circuit. Singing around the local circuit of 15 one end from transmitter to receiver is not possible since an impulse starting on either side of the circuit automatically cuts off the other side.

Another difficulty which arises in the operation of circuits such as those above described is due to the fact that the transmission loss from the local radio transmitter into the local radio receiver is sometimes small enough so that noise currents radiated 20 from the transmitter are sufficient to pass through the receiver and operate one of the echo suppressor units. For example, in Fig. 1, if these noise currents picked up by the radio receiver RR should operate the echo 25 suppressor unit VW the echo suppressor unit VE would be short-circuited. Similarly, in the circuit of Fig. 2 the operation of the echo suppressor unit VE' would short-circuit the echo suppressor unit VW' . 30 If the subscriber at the west station attempted to talk the system would be inoperative for the voice currents would not actuate the echo suppressor unit VE to open up the path from west to east. Similarly, if the 35 subscriber at the east station undertook to talk the system would be inoperative in this direction also because the voice currents would not actuate the echo suppressor unit VW' to render the circuit operative from 40 east to west.

For this reason it is desirable that there be a certain amount of discrimination between the transmitting and receiving channels at the radio receiver. Where the same wave 45 length is employed for transmission in both directions, however, selectivity cannot be taken advantage of in order to attain the desired discrimination and reliance must be placed on directional and balancing methods to obtain sufficient discrimination to avoid noise, the two sets of voice-operated devices, as described above, serving to prevent singing, if the noise is kept down sufficiently to prevent locking up the circuit in 50 the manner just described.

A wave antenna such as AR is substantially unidirectional, that is, it will receive waves transmitted from east to west but will be substantially unresponsive to waves transmitted in the opposite direction. Such 70 an antenna, however, is not completely unidirectional and will therefore respond to a small extent to waves transmitted from the local transmitting antenna AT , although it may be located in a direction quite different 75 from the distant transmitting antenna AT' . In order to balance out the component corresponding to the energy transmitted from the antenna AT , a local loop antenna AB may be provided, this loop being rotatable 80 in a well known manner so that it will be arranged to pick up energy from the transmitting antenna AT but to pick up little or no energy from the distant transmitting antenna AT' . The directive loop AB is 85 connected through an amplifier 21 and through an adjustable phase changer 22 and potentiometer 23 to a vacuum tube amplifier 24. The output circuit of the vacuum tube amplifier 24 is connected through a coil 25, 90 inductively located with respect to the coil 26. By means of the phase changer 22 the wave received by the antenna AB may be adjusted so that it is 180° out of phase with the component from the local transmitter 95 impressed upon the radio receiver from the antenna AR . The potentiometer 23 may be adjusted so that the balancing component picked up by the antenna AB will be just equal in amplitude to the component derived from the antenna AR . In this manner the voice energy received from the local transmitting station may be so completely balanced out that it will be much smaller in volume than the speech energy received 100 from the distant transmitting antenna AT' and, in fact, so small in amplitude that it will not operate the amplifier-detector units to lock them up. A similar balancing antenna AB' , together with associated phase-changing and amplitude-controlling devices are provided in connection with the the 105 circuit of Fig. 2 so that in this respect, as well as in the others previously noted, the two circuits are identical in construction and 110 operation.

The arrangement above described has the advantage that it enables two-way operation with balance both at radio and voice frequencies so poor that singing or poor 120 quality would result if the voice-operated units were not present. By the use of the balancing methods above described, supplemented by the echo suppressor arrangements, the same wave length may be employed for transmission over the radio channels in opposite directions. The echo suppressor units employed as above described, in addition to performing the functions already discussed, further act to suppress 125 130

echoes in the circuits in a manner similar to that in which echoes are suppressed in ordinary four-wire circuits. Since the circuit is operative only in one direction at a time and since singing is impossible, the various gain controls in the system may be set up to their optimum positions for operation independently of each other and without regard to any singing difficulties.

The system above described has a further advantage in that it renders it more difficult for unauthorized persons to listen in on the system by means of radio apparatus. A person desiring to hear the conversations in both directions must provide himself with two receivers. If he only utilized one receiver and the receiver were made sufficiently sensitive to receive the transmission from the distant radiating antenna, the receiving set would be overloaded by the energy from the local antenna. It is therefore necessary to provide one receiving set with suitable directive receiving means and make it sufficiently sensitive to receive from the distant antenna while discriminating against the local stations sufficiently to avoid serious noise. Another set will then have to be provided for receiving from the local station, although in general it would not be necessary to balance this set with respect to transmission from the distant station as the level of the energy from the distant station would be so low with respect to that from the local station as to be substantially inaudible.

It will be obvious that the general principles herein disclosed may be embodied in many other organizations widely different from those illustrated without departing from the spirit and scope of the invention as defined in the following claims.

What is claimed is:

1. In a radio system for two-way communication between two distant localities comprising a radio transmitter and a radio receiver in each locality, four-wire connections for connecting said transmitter and receiver to a two-wire circuit in each locality, an echo suppressor unit associated with each side of the four-wire circuit in each of the localities, and means controlled by said echo suppressors operating in response to transmission in one direction to disable the complete system for transmission in the opposite direction.

2. In a radio system for two-way communication between two distant localities comprising a radio transmitter and a radio receiver in each locality, four-wire connections for connecting said transmitter and receiver to a local two-wire circuit in each locality, an echo suppressor unit associated with each side of the four-wire circuit in each of the localities, and means controlled by an echo suppressor unit in each locality

for normally disabling one side of the local four-wire connection in each locality to prevent circulation of energy in the local four-wire connection, the echo suppressors in each locality being also arranged to render the disabled side of the local four-wire connection operative and the other side of the connection inoperative in response to voice currents.

3. In a radio system for two-way communication between two distant localities comprising a radio transmitter and a radio receiver in each locality, four-wire connections for connecting said transmitter and receiver to a local two-wire circuit in each locality, an echo suppressor unit associated with each side of the four-wire connection in each of the localities, means controlled by an echo suppressor unit in one locality for normally disabling the west to east side of the local four-wire connection, means controlled by a corresponding echo suppressor unit in the other locality for normally disabling the east to west side of the local four-wire connection, and means controlled by each echo suppressor unit associated with one side of the local four-wire connection in each locality for disabling the opposite side of the four-wire connection, said suppressors operating in response to the transmission in one direction to render the side of the local four-wire connection transmitting in that direction operative in one locality and for rendering the other side of the four-wire connection in that locality inoperative, the suppressors in the distant locality operating to maintain disabled the half of the local four-wire connection transmitting in the opposite direction.

4. In a radio system for two-way communication between two distant localities comprising a radio transmitter and a radio receiver in each locality, four-wire connections for connecting said transmitter and receiver to a local two-wire circuit in each locality, an echo suppressor unit associated with each side of the four-wire connection in each of the localities, means controlled by said echo suppressor units in each locality for preventing circulation of energy over the local four-wire connection in each locality when the system is idle, and means controlled by said units in each locality in response to the transmission of energy in one direction for disabling the complete system for transmission in the opposite direction.

5. In a radio system for two-way communication between two distant localities comprising a radio transmitter and a radio receiver in each locality, four-wire connections for connecting said transmitter and receiver to a local two-wire circuit in each locality, an echo suppressor unit associated with each side of the four-wire connection in each of the localities, means controlled by

said echo suppressor units in each locality for preventing circulation of energy over the local four-wire connection in each locality when the system is idle, means controlled by said units in each locality in response to the transmission of energy in one direction for disabling the complete system for transmission in the opposite direction, and means associated with the local radio receiver in each locality for balancing out energy radiated from the local transmitter in order to prevent noise currents from locking up one of the echo suppressors in the idle condition of the circuit.

15. In a radio system for two-way communication between two distant localities comprising a radio transmitter and a radio receiver in each locality, four-wire connections for connecting said transmitter and receiver to a local two-wire circuit in each locality, an echo suppressor unit associated with each side of the four-wire connection

in each of the localities, means controlled by said echo suppressor units in each locality for preventing circulation of energy over the local four-wire connection in each locality when the system is idle, means controlled by said units in each locality in response to the transmission of energy in one direction for disabling the complete system for transmission in the opposite direction, and means associated with the radio receiver in each distant locality for impressing upon said radio receiver a component equal in amplitude and opposite in phase to the energy component received from the local transmitter, thereby preventing noise currents radiated from the local transmitter from locking up one of the echo suppressor units.

In testimony whereof, we have signed our names to this specification this 16th day of December 1924.

RALPH BOWN.
HAROLD S. HAMILTON.
